UNITED STATES PATENT OFFICE.

WILLIAM A. DOBLE, OF SAN FRANCISCO, CALIFORNIA, ASSIGNOR TO THE PELTON WATER WHEEL COMPANY, OF SAN FRANCISCO, CALIFORNIA, A CORPORATION OF CALIFORNIA.

GOVERNING MECHANISM.

1,109,209.

Specification of Letters Patent. Patented Sept. 1, 1914.

Application filed June 2, 1913. Serial No. 771,309.

To all whom it may concern:

Be it known that I, WILLIAM A. DOBLE, a citizen of the United States, and resident of San Francisco, county of San Francisco, State of California, have invented certain new and useful Improvements in Governing Mechanism, of which the following is a specification.

This invention relates to governing mechanism and more particularly to means for limiting the load which may be carried by the prime mover, which is controlled by the governing mechanism.

The invention is especially applicable to hydro-electric power plants where conditions sometimes exist which limit temporarily the quantity of water which may be used. In the case of the usual type of governors, when a heavy load comes on the motor the governor will open the gate to its full capacity, if necessary, in order to keep up the speed and more water might pass through the gate than conditions allow. It is also desired sometimes to limit the output of the plant for other purposes than limiting the water consumption.

The object, therefore, of this invention, is to provide means which may be attached to the usual governing mechanism and which is adapted to positively limit the extent of the opening of the controlling valve or gate which supplies the motive fluid to the prime mover.

I have illustrated the invention in connection with an impulse water wheel which is controlled by a needle gate valve actuated by an auxiliary hydraulic motor which is controlled by a centrifugal governor. It will be obvious from the following description that the invention may be applied to the other forms of governors and is, therefore, not limited to the precise construction which I have shown.

In the drawings, Figure 1 is an elevation, partly in section, of an impulse water wheel and the controlling mechanism therefor, having my invention applied thereto. Fig. 2 is a transverse section on the line 2-2 of Fig. 1.

Referring to the drawings, 10 indicates the shaft of an impulse wheel 11, which carries the buckets 12, the wheel being enclosed in a housing 13, all of the usual construction. A conduit 14 supplies water to

valve 15, which controls the quantity of water passing through the nozzle 16.

The speed of the motor is maintained uniform under changing loads by varying the quantity of water discharged by the nozzle 16. In order to effect this control the valve 15 is provided with a rearwardly extending stem 17 which passes through a stuffing box 18 in the conduit 14. A governor 19, which may be of the centrifugal type, is driven from the shaft 10 by means of the belt 20 and actuates a pilot valve in the valve-body 21. Water or other fluid under pressure is delivered to the valve-body 21 and is admitted and discharged from the cylinder 22 by means of the pilot valve in the usual manner. The cylinder 22 has the usual piston therein to which is connected the piston-rod 23, provided with the cross-head 24. Connecting links 25 connect the cross-head 24 with the end of the bell-crank 26, which is mounted on the fixed pivot 27. The upright arm 28 of the bell-crank is connected with the valve stem 17 by means of the links 29. The various parts of the governing mechanism which have just been described are supported on a base 30 which has an opening in its upper side to permit oscillation of the bell-crank 26 and has arranged on the opposite sides of said opening the brackets or stands 31 to which the block 32 is pivotally connected.

The bell-crank 26 has pivoted thereto the rod 33, having its upper end screw-threaded to receive the nut 34. Arranged on the upper side of the block 32 is a spring 35, which surrounds the rod 33 and acts as a buffer for the nut 34, this spring being of such strength as to overcome the actuating force applied to the bell crank 26.

The operation of the mechanism is as follows: When it is desired to limit the load which may be carried by the motor, or when it is desired to limit the quantity of water which may be discharged by the nozzle 16, the nut 34 is adjusted to permit, when in the position shown in the drawings, the maximum desired opening of the valve 15. It will be observed that when the nut is in contact with the buffer 35 the opening of the valve 15 has reached the limit, but the valve may be moved freely toward the closed position so that the governing mechanism is adapted to freely control the motor for all loads below the desired maximum.

When the maximum load is reached or the maximum quantity of water is being discharged by the nozzle 16, the nut 34 will come into contact with the buffer 35 and 5 positively prevent further opening of the valve 15, thereby effectually limiting the quantity of water discharged.

It will be understood that in some instances the centrifugal governor 19 may be 10 connected directly with the bell-crank 26 or with any other equivalent element of the governing mechanism and therefore as the application of the invention shown is intended to be merely illustrative, I do not 15 wish to be limited to these precise details of construction.

Having thus described my invention, what I claim is:

1. A governor comprising speed responsive means, speed controlling means actuated by said speed responsive means, and means for limiting the speed increasing action of said speed controlling means, and including a fixed abutment, a buffer on said

fixed abutment, a rod adapted to be moved 25 by said speed responsive means, and an adjustable nut on said rod and adapted to engage said buffer.

2. A governor comprising speed responsive means, speed controlling means, means 30 connecting said speed responsive means and said speed controlling means and including a lever adapted to be rocked by said speed responsive means, an abutment having trunnions mounted in fixed bearings, a buffer on 35 said abutment, a rod pivotally connected to said lever and passing through said abutment, and an adjustable nut on said rod and adapted to engage said buffer to limit the speed increasing action of said speed controlling means.

In testimony whereof I affix my signature in presence of two witnesses.

WILLIAM A. DOBLE.
